RIBBON-TYPE GAS BURNER-UNIT

John H. Flynn, New Rochelle, N. Y.

Application May 24, 1951, Serial No. 228,095

4 Claims. (Cl. 158—116)

1

The present invention relates, in general, to gas burners and more particularly to a ribbon-type gas burner, that is to say a gas burner which comprises a slotted hollow casing and a plurality of corrugated metal burner ribbons in the slot of the casing. For a complete description of the type of ribbons used with earlier types of gas burners, and contemplated for use with the burner-unit of this invention, reference may be made to applicant's Patent No. 2,499,482, March 7, 1950.

The gas used in this type of burner is usually a combustible mixture of a hydrocarbon gas and air, and when employed under appreciable pressures, as is required for most industrial uses as well as for some domestic uses, it is necessary to provide two distinct types of gas passages characteristic of the above identified burner ribbons, these two types of gas passages being identified as the high velocity gas ports and low velocity gas ports, the low velocity gas ports providing, in effect, piloting flames for supporting the combustion of the gas mixture flowing from the high velocity ports. This circumstance is due, in part, to the flame propagation rate of the gaseous mixture being used, and in this connection it has been found necessary heretofore to construct individual ribbon-type burners to meet the flame propagation rate of a particular gas mixture being used, that is to say, depending upon whether it is a natural gas, a manufactured gas, or propane. Moreover, due to this same factor, the single ribbon-type burner is of limited capacity, since for pressures above substantially one-tenth inches, the piloting effect of the low velocity gas ports is largely lost.

An object of the present invention is to provide a superior ribbon-type burner-unit of high capacity.

A further object of the present invention is to provide a superior ribbon-type burner-unit which may be used without alteration with all types of hydrocarbon gases and which will operate satisfactorily in air streams of relatively high velocity.

A further object of the invention is to provide a superior ribbon-type gas burner-unit having high velocity and low velocity grooves, each provided with high velocity and low velocity burner ribbons.

A further object of the invention is to provide a superior ribbon-type gas burner-unit of the type hereinabove described, having improved means for cleaning out dirt and other foreign matter which may accumulate in the burner grooves.

2

A still further object of the invention is to provide a ribbon type gas burner-unit of high capacity wherein each individual groove of the burner-unit may act as an independent self-supporting burner.

A still further object of the invention is to provide a superior ribbon-type gas burner-unit of high capacity, having a grooved casing of rigid homogeneous construction, and shaped to control the flow of air thereover, such that the burner will operate satisfactorily when installed in an air stream of high velocity.

Other objects and advantages will appear to those skilled in the art from the following, considered in conjunction with the accompanying drawings.

In the accompanying drawings, in which certain modes of carrying out the present invention are shown for illustrative purposes:

Fig. 1 is a side elevation partly in section of the improved ribbon-type burner-unit of this invention;

Fig. 2 is a top plan view of the burner-unit of Fig. 1;

Fig. 3 is a transverse section of the burner-unit on line 3—3 of Fig. 1;

Fig. 4 is an enlarged fragmentary transverse section of the burner-unit on line 4—4 of Fig. 1;

Fig. 5 is a fragmentary plan view of one of the burner grooves and showing the burner ribbons located therein; and

Fig. 6 is a perspective view of a plurality of burner-units secured together in longitudinal alignment.

As pointed out at the outset, ribbon-type burners heretofore used have consisted of a casing provided with a single slot in which a single set of burner ribbons is mounted, the burner ribbons being adapted to provide self-piloting, that is to say, having as part of their construction high velocity and low velocity burner-ports such as described more fully in the above identified patent, to which a combustible gas mixture is supplied under substantially uniform pressure. While this type of burner has proven successful, the burner-unit of the present invention is designed to have higher capacity as well as greater adaptability to a variety of gas mixtures.

Referring to the drawings, the ribbon-type burner-unit comprises a casing or body 10 formed of cast iron, malleable iron, or the like, the length of the casing exceeding its transverse dimensions. Pursuant to the objects of the invention, the shape of the casing is designed so that the burner-unit will operate successfully, in a relatively high velocity air stream, and to this end

the casing is made substantially ovate or teardrop in cross section, as shown especially well in Fig. 3, the portion 11 thereof of maximum diameter having an aperture 12 extending longitudinally therethrough, which aperture is hereinafter referred to as the gas-supply passage of the burner-casing. The portion of the casing of minimum transverse dimensions is identified by the numeral 13 and comprises a substantially flat burner-surface, indicated generally at 14, extending throughout the length of the casing and provided with upstanding flanges 15 extending along opposite sides respectively thereof and in transversely spaced parallel relationship. The aforesaid flat burner-surface 14 is thus in a plane below the upper edges of the upstanding flanges 15—15 of the casing and hence is sometimes hereinafter referred to as the flat recessed burner-surface of the burner, the upstanding flanges of which serve to protect the combustible gases or flames of the burner against dilution, deflection and undercutting by air currents passing over the burner.

Each end of the casing is provided with an integral substantially disk-shaped flange 16 having circumferentially spaced apertures 17 therein to accommodate bolts whereby two or more burner-units may be secured together in substantially axial alignment in the manner shown in Fig. 5 to provide a multi-unit burner of relatively long length. In this regard, the portion of each flange opposite the corresponding end of the aforesaid recessed burner surface 14 of the casing is cut out as indicated at 18 so that when the several burner-units are secured together as hereinabove described and shown, the flat burner-surfaces of the several units will constitute a single substantially continuous uninterrupted burner-surface. Further, when a plurality of burner-units are thus assembled, the flanges 16 at the opposite ends respectively of the multi-unit burner have axially-apertured substantially disk-shaped flanges 19 bolted to the outer faces thereof, the axial apertures of the flanges 19 being internally threaded for connecting the multi-unit burner to a source of gas supply. A portion of each of these apertured end flanges serves also to close off the corresponding ends of the single continuous recessed burner-surface of the multi-unit burner.

Returning now more particularly to Figs. 3 and 4, the flat recessed burner-surface 14 of the burner-unit is provided with a plurality of narrow but relatively deep grooves 20, 21 and 22 respectively which extend longitudinally thereof and in spaced substantially parallel relationship, each groove being adapted to accommodate a set of high velocity and low velocity burner ribbons of the type described in the above identified patent and indicated generally at 23. In the embodiment of the invention shown herein, three burner-ribbon supporting-grooves are shown in the recessed burner-surface of the burner-unit, but it will be understood that more than three grooves may be used should it be desired to increase the capacity of the burner.

Each of the longitudinal grooves in the recessed burner-surface of the burner-unit is open at its upper end to the atmosphere. The center groove 21, which may be described as a groove coincident with a substantially vertical plane through the longitudinal axis of the burner-unit, is adapted to be connected directly to the gas-supply passage 12 of the burner-unit and supplied with gas therefrom at relatively high velocity. To these ends, the bottom of the center groove intersects

the dome of a bell-shaped channel 24 formed in the top of the gas-supply passage 12 and extending longitudinally thereof, the channel 24 being provided with a plurality of transverse webs 25 which are integral with the walls of the casing and serve to hold the casing from spreading apart transversely of its longitudinal axis. Moreover, the transverse webs 25 serve also, in effect, to divide the bottom of the center groove 21 into a plurality of longitudinally spaced apertures which serve to deliver the combustible gas-mixture in the supply pipe to the burner ribbon in the center groove. Since the aforesaid spaced apertures in the bottom of the center groove are relatively large, the passage of gas therethrough is relatively unrestricted and hence is delivered to the center groove at a relatively high velocity. The center groove is, therefore, sometimes hereinafter referred to as the high velocity burner groove of the casing.

The two outer burner grooves 20 and 22 respectively are not connected directly to the gas-supply passage 12 of the casing but are indirectly connected thereto by a plurality of gas-feeding passages which connect the outer burner grooves to the center or high velocity groove 21. Referring especially to Fig. 3, the aforesaid gas-feeding passages of the outer burner grooves are indicated at 26 and are of relatively small diameter, each extending substantially transversely of the longitudinal axis of the burner and intersecting at its inner end the high velocity burner groove and at its outer end one of the outer burner grooves of the casing. For improved performance, the gas-feeding passages slope upwardly and outwardly at a slight angle relative to the plane of the bottom of the central high velocity groove. Since these gas-feeding passages are of relatively small diameter, the flow of gas from the center burner groove to each of the outer burner grooves is thus retarded and hence the combustible gas mixture flows into the outer burner grooves at relatively low velocity. In this connection, the outer burner grooves 20 and 22 are sometimes hereinafter referred to as the low velocity burner grooves of the burner-unit.

The aforesaid burner ribbons 23 are of the type illustrated more fully in the above identified patent, and in the preferred form comprise two pairs of major ribbons, each pair being indicated by the numeral 27, and one pair of minor ribbons indicated generally at 28 and shown especially well in Fig. 5. This arrangement of the major and minor ribbons results in the formation of a plurality of what may be aptly termed low velocity gas ports 29, a plurality of medium or intermediate velocity gas ports 30, and a plurality of high velocity gas ports 31, the latter extending along the outer edges of the burner, while the low velocity and intermediate velocity gas ports are disposed between the outer high velocity gas ports. In explanation of the velocity characteristics of the aforesaid gas ports, it may be stated that the small cross sectional area of each of the low velocity gas ports 29 is commensurate with a relatively large surface area and hence a relatively high skin friction effect, with the result that gas emerging from the gas ports 29 will be slowed down and prevented from projecting any appreciable distance from the burner-ribbons. On the other hand, the surface or wall areas of the intermediate gas ports are somewhat less than those of the low velocity gas ports, with the result that there is less skin friction and hence the gas issues therefrom at greater velocity. In like manner, each of the

high velocity gas ports 31 has a larger cross-sectional area as compared to the respective cross-sectional areas of both the gas ports 29 and gas ports 30 and hence less wall area, with the result that there will be less skin friction, and gas emerging from the gas ports 31 will project a greater distance from the burner ribbons.

The burner ribbons illustrated in Fig. 5 will, therefore, produce three different heights of flames, the long flames provided by the high velocity gas ports 31—31 extending along the outer edges respectively of the burner and maintained by the flames provided by both the low velocity gas ports 29 and intermediate gas ports 30, while the flames of the latter are, in turn, sustained by the flames provided by the low velocity gas ports 29.

The burner ribbons hereinabove described and indicated generally at 23 in Fig. 4, are retained in place in the burner-grooves 20, 21 and 22 respectively of the casing in any suitable manner such, for instance, as by transverse pins 32 shown especially well in Figs. 1, 2 and 4. In this connection, it will be noted that the ribbons 23 are supported with the upper edges thereof slightly below the burner-surface 14 of the casing, as a consequence of which the vertical walls of the burner grooves, in conjunction with upstanding flanges 15—15 of the casing, serve to shield the flames projecting from the burner ribbons. This is a particularly important aspect of the improved burner of this invention when installed in a high velocity air stream.

Referring again to the restricted passages 26 of the low velocity burner grooves 20 and 22, it will be seen from Fig. 1 that these apertures are spaced apart longitudinally of the length of the casing and may be formed by drilling into the side walls of the casing from the outer surface thereof. As an additional feature of the invention, the portion of each of these drilled apertures between its respective low velocity burner groove and the outer surface of the casing is counterbored as indicated at 33, and provided with a screw-plug 34 to close the counterbored portion of the passage. In accordance with this construction, it is relatively easy to clean out dirt, and other foreign matter from the casing by the relatively simple expedient of unscrewing the plugs 34 along the length of the casing so as to have access to the burner grooves.

As has been mentioned above, each burner-unit constitutes an operable burner in and of itself. However, by providing each unit with integral apertured flanges 16—16 at opposite ends respectively thereof, two or more units may be secured together by fastening bolts 35, as shown in Fig. 6, to build up a burner of increased capacity. Moreover, while the inlet to the gas-supply passage 12 of each burner-unit is shown at one end thereof, it will be understood that a gas pipe connection to each unit may be made in the bottom of the casing or in one wall thereof, depending upon the circumstances of installation.

It is manifest, therefore, from the foregoing description, that the burner of this invention is characterized by a casing of homogeneous construction and of a tear-drop design, sometimes hereinafter referred to as a casing of ovate cross section, to insure successful performance of the burner when in a high velocity air stream; and that the burner is characterized by the combination of a casing having high velocity burner grooves and low velocity burner grooves, in each

of which types of grooves are sets of burner ribbons, each set of burner ribbons incorporating a plurality of high velocity gas ports, low velocity gas ports and intermediate velocity gas ports.

5 This construction has been found to provide a burner-unit of unexpectedly high capacity, due to the fact that the center flame of the high velocity burner groove is sustained and maintained by the flames of the low velocity burner grooves on opposite sides thereof, by which arrangement relatively high gas pressures may be used with a consequent increase in the capacity of the burner. By way of example, a burner having a flame space of substantially 72 inches may have a capacity substantially of 600,000 B. t. u. per hour. The improved burner has many industrial uses and has been found to be ideally suited for glass polishing, textile singeing, direct heating of large volumes of air, electrolytic tin flowing and similar applications. It has also been found that the improved burner is characterized by instant lighting and shut-off, and with little or no residual heat.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A ribbon-type gas burner, comprising a single-piece cast elongated casing having a longitudinal through-passage of which either end may serve as the gas inlet to said casing, a slot and groove in said casing open to the outside of the latter and extending in laterally spaced parallel relation longitudinally of said casing throughout its length, and a restricted orifice in said casing providing communication between inner portions of said slot and groove, said slot being throughout its length in open communication with said through-passage and forming a high-velocity gas outlet, and said groove forming a low-velocity gas outlet; and burner ribbons in the outer portions of said slot and groove, respectively, said slot and groove being so spaced that the flame from the latter will support the flame from the former.

2. A ribbon-type gas burner, comprising a single-piece cast elongated casing having a longitudinal through-passage of which either end may serve as the gas inlet to said casing, a slot and groove in said casing open to the outside of the latter and extending in laterally spaced parallel relation longitudinally of said casing throughout its length, and a restricted orifice in said casing providing communication between inner portions of said slot and groove, said slot being substantially throughout its length in open communication with said passage and forming a high-velocity gas outlet, and said groove forming a low-velocity gas outlet, and the opposite ends of said casing having integral mounting flanges to permit connection of end-to-end engaged identical casings with their respective gas passages and outlets in alignment and continuous with each other; and burner ribbons in the outer portions of said slot and groove, respectively, said slot and groove being so spaced that the flame from the latter will support the flame from the former.

3. A ribbon-type gas burner, comprising a

single-piece cast elongated casing having a longitudinal cylindrical through-passage of which either end may serve as the gas inlet to said casing, two outer grooves and a slot formed integrally in said casing and being open to outside thereof and extending in laterally spaced parallel relation longitudinally of said casing throughout its length with said slot being intermediate said grooves, restricted orifices providing communication between inner portions of said slot and said grooves, respectively, an internal longitudinal groove between and in open communication with said passage and said inner slot portion and extending throughout the length of said casing, and longitudinally substantially equally spaced integrally-formed transverse partitions substantially wholly within the confines of said internal groove, said slot forming a high-velocity gas outlet and said outer grooves forming low-velocity gas outlets, and the opposite ends of said casing being plane surfaces extending transversely of said slot and grooves to permit end-to-end engagement of identical casings with their respective gas passages and outlets in alignment and continuous with each other; and burner ribbons in the outer portions of said slot and outer grooves, respectively, said slot and outer grooves being so spaced that the flames from the latter will support the flame from the former.

4. A ribbon-type gas burner, comprising a single-piece cast elongated casing having a longitudinal through-passage of which either end

5 may serve as the gas inlet to said casing, a slot and groove in said casing open to the outside of the latter and extending in laterally spaced parallel relation longitudinally of said casing throughout its length, and a restricted orifice in said casing providing communication between inner portions of said slot and groove, said slot being throughout its length in open communication with said through-passage and forming 10 a high-velocity gas outlet, and said groove forming a low-velocity gas outlet, and said casing having means for its end-to-end connection with other identical casings with their respective gas passages and outlets in alignment and continuous with each other; and burner ribbons in the outer portions of said slot and groove, respectively, said slot and groove being so spaced that the flame from the latter will support the flame from the former.
